UNITED STATES PATENT OFFICE.

JOHN R. WRIGHT, OF WHEELING, MISSOURI.

HAY-STACKER.

No. 821,392.

Specification of Letters Patent.

Patented May 22, 1906.

Application filed March 1, 1905. Serial No. 247,950.

To all whom it may concern:

Be it known that I, JOHN R. WRIGHT, a citizen of the United States, residing at Wheeling, in the county of Livingston and State of Missouri, have invented new and useful Improvements in Hay-Stackers, of which the following is a specification.

This invention relates to a hay stacker or ricker of that class embodying a fork or elevating means carried by side bars and operative through the medium of draft appliances connected thereto to facilitate the formation of a stack or rick and under certain operations to positively top off the latter.

The improved stacker in addition to the elevatable fork includes a rotatable counterbalancing-frame having weight means movably secured thereto in opposition to an elongated arm of the frame attached to the fork and over a part of which the draft cord, rope, or cable passes in regular plies and engages movable elements. The fork has automatically-adjustable side bars, and coöperating therewith are movement-controlling devices 25 to modify the elevation of the fork at will.

Other incidental advantageous features will be hereinafter referred to and individually contribute to the efficiency of the stacker organization as an entirety.

In the drawings, Figure 1 is a side elevation of a stacker embodying the features of the invention and showing the fork lowered. Fig. 2 is a top plan view of the same. Fig. 3 is a view similar to Fig. 1, showing the fork and its side bars elevated. Fig. 4 is a detail view of a portion of the fork, showing the adjusting means for a part of the teeth thereof in a different position.

Similar numerals of reference indicate corresponding parts in the several views.

The improved stacker is portable and may be positioned at any point in a field or otherwise located for the purpose of forming a stack or rick, and the base thereof comprises opposite side bars 1, connected to render the same rigid by transverse bars 2 and 3, the bar 2 being located at one end of the base and the bar 3 at the opposite extremity. Posts 4 rise from the extremity of the base, having 45 the cross-bar 2 thereon, and are disposed in parallel relation and have an equal vertical extent. Extending inwardly from intermediate portions of the opposite side bars 1 are inwardly and upwardly inclined frame-bars 5, having their upper ends connected by 55 sills 6 with an intervening space 7 between

the inner opposing edges thereof. These frame-bars 5 and sills 6 unitedly form a supporting means for a counterbalancing-frame, rotatably mounted between the sills 6 and 60 consisting of a bar or strip 8, eccentrically intersected at right angles by another bar or strip 9, the eccentric disposition of the bar or strip 9 with respect to the bar or strip 8 providing the latter with an elongated arm 10 65 and a shorter arm 11, on opposite sides of the point of intersection with the bar 8 of the bar 9. Through the center of the intersecting portions of the bars 8 and 9 a fulcrum-pin 12 extends and is held in suitable bearings 13 on 70 the top central portions of the sills 6. The one end of the bar 9 has yoke-arms 14 secured thereto and extending outwardly therefrom to embrace the opposite terminals of a rod or spindle 15, on which a series of grooved guide 75 rollers or sheaves 16 are mounted and have independent rotation between the said yoke-arms. To the end of the shorter arm 11 of the bar or strip 8 a weight box or receptacle 17 is pivotally hung and free to swing on the 80 end of the arm, and projecting upwardly from opposite sides of the outer end of the said weight box or receptacle are yoke-arms 18, which embrace the opposite ends of a rod or spindle 19, on which a series of grooved 85 rollers or sheaves 20 are mounted between the yoke-arms 18 and have independent rotation. At the end of the longer arm 10 a pulley 21 is movably attached, and adjacent to said pulley at a suitable distance from the 90 point of location of the fastening therefor an eye 22 is also secured to the arm. The end of the arm 10, carrying the pulley 21, is also connected, by means of wires, cables, or other analogous devices 23, to a cross-arm 24, terminally attached to the side members of a fork constructed as will be presently set forth, and in addition the cross-arm 24 has the terminals of limiting chains or analogous devices 25 attached thereto and also connected to the upper portions of the adjacent frame-bars 5 of each pair of said frame-bars. These chains or analogous devices 25 limit the overthrow of the fork and the movement 100 of the side bars to which said fork is connected, and thereby relieve the devices co-operating with the said side bars and the stacker organization generally of considerable strain.

One end of a draft cord, rope, or cable 26 is 110 secured to the eye 22 of the arm 10 and is then passed over one of the grooved rollers or

sheaves 16, held by the yoke-arms 14, and downwardly over one of the grooved rollers or sheaves 20, held by the arms 18 of the weight-box 17, and then passes downwardly

- 5 under a guide-pulley 27, held on the cross-arm 2 of the base. From the pulley 27 the cord, rope, or cable runs upwardly over another grooved roller or sheave 20, held by the weight-box, and over another of the rollers or sheaves 16 between the arms 14 and down to the pulley 21. From the pulley 21 the cord, rope, or cable again passes upwardly over and engages the remaining grooved roller or sheave 16 between the arms 14 and passes down to the remaining grooved roller or sheave 20 on the weight-box and from thence extends under a guide-pulley 28 and is carried away from the end of the machine any suitable distance for the reception 20 of draft appliances for the attachment of either one or more draft-animals, as the work to be performed may require.

It will be seen that the several plies of the draft-cable arranged as set forth have free movement over the grooved rollers or sheave 16 and 20 and through the several pulleys and the draft strain is applied to the outer extremity of the arm 10, close to the point of attachment to the latter of the wires, cables, 30 or other devices 23, running to the cross-arm 24. When the cord, rope, or cable 26 is drawn outwardly to exert a pulling tension on the end of the arm 10, the entire frame, composed of the intersecting bars or strips 8 and 9, will be assisted to overcome the weight resistance of the fork and side bars and the load carried by the fork through the particular position of the weight-box 17, in which suitable weights will be disposed, and 35 as the fork, with its load, and the side bars swing over to dump the load onto the stack, or in the primary preparation of the latter, said weight-box swings over to a reverse position from that which it normally occupies, 40 as clearly shown by Fig. 3. When the fork is relieved of its load, the weights in the box 17 materially assist in the return of the fork and the side bars to normal lowered position, and during such operation the draft cord, 45 rope, or cable is slackened by backing the draft animal or animals attached thereto. In some instances this draft cord, rope, or cable may be attached to and operate in connection with any well-known form of sweep. 50 This arrangement, however, will be determined by the desires of the user.

The frame-bars 5, carrying the sills 6, are also reinforced by brace-rods 29, connected thereto and to the cross-bars 2 and 3, and 55 this bracing means co-operating with the inwardly-inclined disposition of the frame-bars will give the supporting means for the counterbalancing - frame movably disposed on the sills 6 a stable disposition with respect

to the base and resist strain imposed thereon 65 by the weight of the successive loads of the fork.

The fork or rake is composed of a series of long teeth 30, attached to a head - bar 31 and braced or strengthened by an intermediate tie-bar 32, having a beveled edge toward the free ends of the said teeth to avoid the formation of a shoulder obstruction and permit the hay or straw to fall fully over the said teeth toward the head-bar 31. Individually pivoted to the teeth 30 adjacent to the head - bar 31 are a series of shorter teeth 33, which are always held, in the present instance, in either one of two angular positions with respect to the teeth 30. Movingly connected to the head-bar 31 is an adjusting-bar 34, which is adapted to be interposed between the outer edge of the head-bar and the adjacent edges of the teeth 33 or to be elevated and thrown back to permit the inner edges of the said teeth 33 to practically engage with the head-bar, as shown by Fig. 4. Two of the longer teeth 30 are extended inwardly beyond the head-bar 31, as at 35, and have the extensions thereof formed with under bevels 36, attached to slidable members 37 of the side bars, which have their terminals correspondingly beveled to form an elongated break-joint between the two parts, suitable fastening means being employed to 90 connect the extensions 35 with the members 37. The adjusting-bar 34 is wedge-shaped in cross-section, so that when it is interposed between the edge of the head-bar 31 and the teeth 33 its reduced edge will be downward to effect a proper angular position of the said teeth and avoid interposing between the latter and the head-bar too great thickness of material. By having this adjusting-bar wedge-shaped and interposable between 95 the teeth 33 and the head-bar 31 said teeth 33 are permitted to be applied to the teeth 30 in closer relation to the head-bar for practical engagement with said bar during one adjustment of the teeth 33 or when the adjusting-bar is thrown over on top of the head-bar. The wedge-shaped cross-sectional contour of the adjusting-bar also facilitates the elevation of the same from engagement with the edge of the head-bar adjacent to the teeth 33. 100 105 110 115

The side elevating means for the fork in addition to the slidable members 37 include bars 38, which are pivoted at one end to the outer sides of the side bars 1 of the base near the cross-bar 2, and to each slide-bar 37 is attached an embracing-strap 39, carrying an antifrictional roller 40, which bears against the under edge of the bar 38, and at the opposite extremity a strap 41 is attached to the pivoted bar 38 and carries an antifrictional roller 42, bearing on the edge of the slide-bar 37 farthest from the contiguous edges of the two bars 37 and 38. Each of the bars 37 is 120 125

extensible regularly with respect to its companion bar 38; but this extension is controlled by adjusting means, which will now be explained. Attached to the end of each 5 slidable bar 37, near the pivoted end of the bar 38, is a cord, rope, or cable 43, which passes over a grooved roller or sheave 44, held on the outer side of the opposite extremity of the pivoted bar 38 by an embracing-strap 45. The cord, rope, or cable 43 after passing over the grooved roller or sheave 44 extends under the two bars in each instance or at opposite sides of the stacker and is attached to a ring or analogous device 10 46, freely movable on an inclined controlling-bar 47, the said bar being terminally held by the upper end of the post 4 and the cross-bar 3. On each of these controlling-bars 47 a stop-sleeve 48 is adjustably mounted and 15 adapted to be held by a set-screw 49 passing therethrough to engage the bar 47. By adjusting the two sleeves 48 at corresponding elevations on the controlling-bars 47 the movement of the slidable bars 37 will be controlled, and consequently the elevation of the 20 fork correspondingly regulated, it being understood that the sleeves 48 will be moved on the bars 47 proportionately to the height of the stack or rick to effect a deposit of the 25 load of hay or straw carried by the fork on the top of such stack or rick.

Primarily the adjusting stop-sleeves 48 are moved fully up over the controlling rods or bars 47 adjacent to the posts 4, for the reason that there will be no elevation of the stack or rick at such time, and in this connection it will be noted that considerable weight or resistance is removed from the draft animal or animals by reason of the closeness of the 30 load, or, in other words, the shortness of the side bars or reduced leverage. Of course the 35 resistance and leverage will be increased as the slidable bars 37 regularly elevate in accordance with the adjustment of the sleeves 40 48 on the rods or bars 47.

From the foregoing description the operation of the stacker will be readily understood, and the advantages of the particular construction are manifold and reside mainly in 45 the arrangement of the counterbalancing-frame and especially the longer arm 10 thereof, which will facilitate the operation of elevating the fork and its side bars by reason of the longer leverage of the same and the 50 position in respect thereto of the counterbalancing means or weight-box and the plies of the draft cord, rope, or cable. The side bars of the extensible nature set forth coöperating with the controlling means for regulating the elevation of the slidable members 55 of said bars is also another feature of importance, together with the incidental details of the several parts which have heretofore been 60 fully set forth.

The materials of which the stacker parts 55 are composed may be varied at will and may be either wood or metal or partially of both, and to accommodate various applications changes in the proportions, dimensions, and minor details may be made without departing 70 from the spirit of the invention.

Having thus described the invention, what is claimed is—

1. In a stacker, the combination of a base, a support held by the base, a counterbalancing-frame mounted on the support and having an elongated arm, a fork having side bars pivotally connected to the base, the terminal of the elongated arm being attached to portions of the side bars, a counterbalancing-weight means acting in opposition to the said arm, and a draft device movably passing over a portion of the counterbalancing-frame and having one terminal thereof attached to the extremity of the arm adjacent 85 to the point of connection of the latter with the side bars, a portion of the draft device also movably engaging the extremity of the arm attached to the side bar.

2. In a stacker, the combination of a base, 90 a fork movably connected to the base to swing thereover, a counterbalancing-frame rotatably supported by the base and having an elongated arm connected to a portion of the fork, a weight means attached to the opposite extremity of the said arm, and a draft device engaging a portion of the base and passing over a part of the counterbalancing-frame and the weight means and terminally attached to the free extremity of the elongated arm.

3. In a stacker, the combination of a base, a fork pivotally supported by the base and movable thereover, a counterbalancing-frame rotatably held by the base and connected to a part of the fork and having rotatable devices on different portions thereof, a weight-receptacle carried by a part of the frame and also having rotatable devices thereon, and a draft device engaging a part 105 of the base and the said rotatable devices of the counterbalancing-frame and weight-receptacle.

4. In a stacker, the combination of a base, 110 a fork pivotally connected to the base and movable over the latter, a counterbalancing-frame attached to a portion of the fork, and a draft device having plies loosely movable over a portion of the counterbalancing-frame to distribute the draft force over a 120 greater area of the latter, one terminal of the draft device being immovably connected to the extremity of the frame attached to the fork.

5. In a stacker, the combination of a base, 125 a fork pivotally attached to the base and movable thereover, and adjustable devices coöperating with the fork to vary the eleva-

tion of the latter, a part of said devices being terminally slidable over the remaining portion thereof.

6. In a stacker, the combination of a base, side bars composed of members pivoted to the base, and slidable members coöperating with said pivoted members, a fork attached to the slidable members, flexible devices connected to the slidable members and movable over the pivoted members, adjustable means with which the flexible devices loosely engage, said flexible devices being terminally slidable on the adjusting means and draft means for operating the fork and the side bars.

7. In a stacker, the combination of a base, side bars having members pivoted to the base and slidable members coöperating with said pivoted members, a fork attached to the slidable members, a counterbalancing-frame connected to a portion of the side bars, a draft device coöperating with the counterbalancing-frame, adjustable means adjacent to each side bar organization and including shiftable stop devices, and flexible connections between the slidable bars and the said adjustable means, the flexible connections being terminally movable on the adjustable means and adapted to be limited as to movement by the stop devices.

8. In a stacker, the combination of a base, inclined controlling-bars held on the base and having adjusting-sleeves thereon, a fork having extensible side bars pivotally attached to the base, flexible connections between the

portions of the said side bars and the controlling-bars, and draft means coöperating with the fork and side bars.

9. In a stacker, the combination of a base, inclined controlling-bars having slides movably mounted thereon, extensible side bars pivoted to the base, flexible connections between portions of the side bars and the controlling-bars, said connections loosely engaging the controlling-bars, a fork carried by the side bars, and a draft means coöperating with the side bars and fork.

10. In a stacker, a fork composed of a series of main teeth, a head-bar attached to said teeth, shorter teeth pivoted to the main teeth, and an adjusting-bar continuing entirely across the fork and movably connected to the head-bar and insertible between the outer edge of the latter and the shorter teeth, the said adjusting-bar being approximately wedge-shaped in cross-section and disposed in a plane at right angles to the main teeth when inserted between the head-bar and the shorter pivoted teeth, the adjusting-bar when out of engagement with the shorter pivoted teeth being thrown over on the head-bar.

In testimony whereof I have hereunto set my hand in presence of two subscribing witnesses.

JOHN R. WRIGHT.
